UNITED STATES PATENT OFFICE.

GEORGE L. MASON, OF NEWARK, NEW JERSEY, ASSIGNOR TO GEORGE L. MASON COMPANY,
OF NEW YORK, N. Y., A CORPORATION OF NEW YORK.

SIGN-LETTER.

No. 885,936.

Specification of Letters Patent.

Patented April 28, 1908.

Application filed April 28, 1905, Serial No. 257,892. Renewed August 27, 1907. Serial No. 390,380.

To all whom it may concern:

Be it known that I, GEORGE L. MASON, a citizen of the United States of America, and resident of the city of Newark, county of 5 Essex, and State of New Jersey, have invented certain new and useful Improvements in Sign-Letters, of which the following is a specification.

My invention relates to certain new and 10 useful improvements in sign letters and has for its object the production of a sign which is cheap, and attractive and which can be readily formed to read in any way desired.

My invention consists in certain constructions and combinations which will be first described and then the invention pointed out in the claims.

Referring to the drawings which form a part of this application and on which the 20 same reference numeral is used to denote the same part wherever it occurs, Figure 1 is a front view of a card showing the preferred form of my invention before any of the sections have been removed. Fig. 2 is a view 25 similar to Fig. 1 showing the sections removed to form the letter E. Fig. 3 is a section through the card and showing the backing which I prefer to use and, Fig. 4 is a detail view showing one of my preferred forms 30 of removable sections.

1 designates a sheet of any suitable material which is provided with the removable sections 2. These sections are arranged along predetermined lines so as to form a 35 monogram so that by removing the proper combination of sections any letter or character may be formed. In Fig. 2, I have shown how the letter E is formed by the removal of the proper combination of sections. In 40 the form of my invention shown, these removable sections 2 are in the form of circular disks and are formed by incisions 3 which do not completely encircle the sections, leaving the sections connected to the sheet by the 45 uncut portions 4, whereby the sections 2 will be held in the sheet but may be removed by simply forcing the section out thus tearing the uncut portions as illustrated in Fig. 4. It will be apparent however, that other forms 50 of removable sections than those illustrated may be used and also other means for holding the sections in position.

I have shown a piece of tissue or like material 5 secured to the sheet 1, preferably 55 along only one side, it may however be se-

cured in any way desired and may be colored in order to have the letters show colored.

In the operation of my device, a series of sheets are taken and the proper combinations of sections are removed to form the desired letters and then the sheets are suitably mounted so as to be illuminated from behind, for instance, they may be secured to a show window. It will be noted that the openings formed by the removal of the sections 60 will all be capable of being illuminated from a common source of light. If preferred, a single sheet can be provided with several groups of sections so that the desired sign 65 can be formed from a single sheet.

While I have described what I deem to be the preferred form of my invention, I desire to have it understood that my invention is not limited to the construction shown and described as many changes may be made in 70 the form, construction and arrangement of parts without departing from the spirit of my invention, as set forth in the amended claims.

What I claim as new and desire to secure 80 by Letters Patent is:—

1. A sheet provided with a plurality of removable sections arranged along predetermined lines and in substantially the plane of the sheet, whereby by removing certain 85 of said sections different designs may be formed the openings formed by the removal of the sections being capable of having light transmitted through them from a common source.

2. A sheet provided with a plurality of removable sections arranged in the form of a monogram and in substantially the plane of the sheet, whereby by removing certain of 90 said sections any letter or character may be 95 formed, the openings formed by the removal of the sections being capable of having light transmitted through them from a common source.

3. A sheet provided with a plurality of removable sections formed by incisions which form, but do not sever the sections from the sheet, said sections being arranged along predetermined lines, whereby by removing certain of 100 said sections different designs may be 105 formed.

4. A sheet provided with a plurality of removable sections formed by incisions which form, but do not sever the sections from the sheet, said sections being arranged to form a 110

monogram whereby by removing certain of said sections any letter or character may be formed.

5. A sheet provided with a plurality of removable sections arranged along predetermined lines, and in substantially the plane of the sheet, whereby by removing certain of said sections different designs may be formed and a backing sheet secured to said first mentioned sheet.

10. A sheet provided with a plurality of removable sections formed by incisions which

form, but do not sever the sections from the sheet, said sections being arranged along predetermined lines, whereby by removing certain of said sections different designs may be formed and a backing sheet secured to said first mentioned sheet. 15

Signed by me at Washington, District of Columbia this 27th day of April, 1905.

GEORGE L. MASON.
